UNITED STATES PATENT OFFICE.

ALEXANDER MEISSNER, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

BALANCING CIRCUIT FOR TELEPHONIC TRANSMISSION.

Application filed May 3, 1922. Serial No. 558,302.

To all whom it may concern:

Be it known that I, ALEXANDER MEISSNER, a citizen of Germany, residing at Berlin, Germany, have invented certain new and useful Improvements in Balancing Circuits for Telephonic Transmission, of which the following is a specification.

This invention relates to a system of signalling, more particularly telephony, using both land lines and wireless. In systems of this kind, a central station is equipped with radio receiving and sending apparatus and provision is made for connecting this apparatus to the subscribers' land lines connecting with the central station.

In telephonic transmission through wires with the aid of high frequency currents and wireless telephony, a balancing circuit or Wheatstone bridge arrangement is employed which comprises the transmission line, an artificial line made up of resistance and tuning elements, a transformer associated with the sender, and a circuit which is branched off from the middle of the one coil of the transformer to the joinder of the transmission line arm and the artificial line arm and is designed to receive the current from the distant station. Similar circuit arrangements are also used for terminal or intermediate amplifying bridges in ordinary telephonic transmission over wires. If, in such arrangements, the artificial line is properly balanced with respect to the real or transmission line, a reaction of the receiving circuit on the sender is obviated, and the production of howling noises in the installation is prevented.

The invention will be explained with reference to the accompanying drawings in which—

Fig. 1 shows a simple bridge arrangement of the well known type,

Fig. 2 shows one feature of an arrangement according to the invention,

Fig. 3 shows a practically operative arrangement according to the invention; and

Fig. 4 illustrates the regions of the characteristic current curve of a thermionic valve that are used in receiving and sending.

In the ordinary bridge arrangement shown in Fig. 1, the transmission line 1 forms one arm of the bridge, the second arm 2 of which consists of an artificial line. The other two

arms are constituted by one of the windings of a transformer 3 from whose middle point a circuit containing receiving elements 5 is branched off. The second winding of the transformer 3 is connected with a sender 4. The sender 4 and receiver 5 may be adapted for high frequency telephony.

A great drawback of the arrangement shown in Fig. 1 results from the fact that the resistance and other electrical properties of the transmission line do not remain constant. The resistance of this line will differ from 300 to 1000 ohms and more, according to the distance of the subscriber's station connected with the transmission line 1 from the bridge arrangement. Since the bridge can only be balanced for a certain line resistance, the receiver will react upon the sender to a greater or lesser extent according as the balancing is more or less imperfect, and hence humming sounds or howling will be produced in the system.

In Fig. 1 the receiver 5 may be of the ordinary detector type, and the sender 4 may comprise a thermionic valve, although it is indifferent whether a machine generator, an electric arc or a thermionic valve is employed. The transmission line 1 is an ordinary line leading to a subscriber. The purpose of the bridge arrangement is to prevent the speech currents that proceed from the receiving device from affecting or creeping into the high frequency sender. This object will be accomplished whenever the bridge is perfectly balanced. But if this is not the case due, for instance, to a defect in the line or to a different subscriber's apparatus having been connected up, it may happen that the resistance W^1 of the one arm of the bridge becomes smaller than the resistance W^2 of the artificial line 2. The current J^1 will then be greater than the current J^2 , and the differential current will then give rise to a flux in the transformer 3. If, under such conditions, a vocal sound or a letter such as "a" now arrives at the receiver 5, this letter "a" will be simultaneously sent

out by the sender 4 and received at the corresponding distant station in which, of course, the bridge will also never be perfectly balanced. The receiver at the distant station will pass on the "a" to the sender at that station, which will send it back to the

receiver at the first station and so forth. A continuous cycle or sequence of amplifying effects is thus produced and the result may be a complete distortion of the letter or vocal sound.

To set up disturbing oscillations of this kind in the entire system it is not necessary to transmit vocal sounds, because one or the other of the various transformers 10 will be sure to possess a pronounced natural vibration, and any external action such as the switching on of the system may be sufficient to start the vibrations, which will then be amplified to such a degree that the 15 whole system will start humming.

This great drawback of all balancing circuit arrangements is removed by the present invention. The arrangement according to this invention is such that whenever a flux 20 due to imperfect balancing is translated from the receiving circuit to, or caused to arise in, the transformer, the effect of this flux is made to act on the sending circuit or its thermionic valve in such a manner 25 that all reactions of the receiving circuit on the sender are compensated or neutralized.

One feature of the invention is exemplified in Fig. 2. The circuit arrangement 30 in this figure differs from those of Fig. 1 in the first place in the fact that the receiving circuit is not directly connected to the sender transformer 3 but to a separate coil 6 which forms two arms of the Wheatstone bridge arrangement. One of the windings of the transformer 3 is connected 35 in parallel to the coil 6. If a flux is set up in the coil 6 due to an unbalancing caused by variation of the resistance of the 40 line, a part of the current flowing in the receiving circuit will act through the above-mentioned winding of the transformer 3 on the sending circuit 4.

In accordance with the invention, a 45 second winding 7 is placed on the core of the coil 6. The potential induced in winding 7 is always proportional to the degree of unbalance of the bridge arrangement, it being understood that the core of the 50 coil 6 extends on both sides of the point of connection of the receiver 5 to the coil, so that the currents J_1 and J_2 tend to neutralize each other as to their effect on the coil 6 and the winding 7. Since the winding 7 is connected in series with the secondary winding of the sending transformer 3, it will act to compensate or neutralize 55 whatever potential may have been directly produced in the secondary of the transformer 3 by currents in the receiving circuit.

In the circuit arrangement shown in Fig. 60 3, the neutralizing or compensating voltage induced in the winding 7 is made to act on the sender 4 through a thermionic valve 8

that acts as a limiting device. The input circuit of the valve 8 is connected to winding 7 while the output circuit is connected to the primary of coupling 9. The secondary of coupling 9 is in series with the 70 secondary of transformer 3 and the sender. The purpose of this limiting valve is to prevent the voice currents sent over the line 1, which, of course, must be able to act upon the transformer 3, from also being compensated, as this would prevent these voice currents from being passed on. The heating current and anode voltage of the limiting valve 8 are made such that the voltage impressed on the grid of valve 8 80 due to the receiving circuit and reproduced in the sending circuit correspond to the region lying between the points a and b of the characteristic curve, shown by Fig. 4.

The characteristic curve shown in Fig. 4 85 is the usual curve in which the abscissæ represent the grid voltage and the ordinates represent plate current.

In this case the valve 8 acts as an ordinary amplifier with no limiting action. The 90 voltages induced in the sender circuit by means of coupling 9 and transformer 3 are equal and opposite and hence the effect of the unbalance of the Wheatstone bridge on the sender is eliminated.

The voltage of the voice currents coming from the line 1 is usually from 10 to 20 times as great as the voltage of the currents coming from the receiver and hence the voltage impressed on the grid of valve 8 100 due to these currents covers a much wider range, as denoted for example, by the points c and d . In this case, the valve 8 gives a limiting action and the voltages induced in the sender circuit by means of coupling 9 and transformer 3 are not equal, but the voltage induced by means of transformer 3 predominates. Therefore, although the effects on the sender due to the receiving 110 circuit are balanced, no neutralization of the voice currents from the line 1 takes place.

The aforescribed separation of the transformer 3 from the balancing coil 6 in accordance with Figs. 2 and 3 makes it 115 easier in many respects to obtain the desired balance. The currents due to imperfect balancing devide, and flow part through the transformer 3, and part through the line 1, the greater part flowing through the line, because it has a much smaller resistance than the transformer. The arrangement of Fig. 3 therefore reduces the effect that a change of resistance 120 of the line has on the sender. The sending back or return of energy to the sender circuit is also facilitated, because the transformer 3 need not be altered. The coil 7 can be coupled with a separate balancing coil more easily than with a transformer.

I claim:

1. In a balancing circuit arrangement for telephonic transmission, a bridge circuit comprising a transmission line and an artificial line, a receiver connected across the junction of the transmission line and the artificial line on the one hand and the junction of the other two arms of the bridge circuit on the other hand, a sender coupled to the bridge circuit, and means including a circuit coupled with the bridge circuit for neutralizing the current communicated to the sender by the bridge circuit due to unbalance in said bridge caused by unequal impedance of transmission line and artificial line. 10
2. In a balancing circuit arrangement for telephonic transmission, a bridge circuit comprising a transmission line constituting one of the arms of the bridge, an artificial line constituting a second arm of the bridge, a coil constituting the other two arms of the bridge, and a receiver connected across the junction of the transmission line and the artificial line, on the one hand, and an intermediate point of the coil, on the other hand, a sender coupled to said coil, and means including a circuit coupled with said coil for neutralizing the current impressed upon the sender by the bridge circuit due to unbalance in said bridge caused by unequal impedance of transmission line and artificial line. 20
3. In a balancing circuit arrangement for telephonic transmission, a bridge circuit comprising a transmission line, and an artificial line constituting two arms of the bridge circuit, and a coil connected across the terminals of the transmission line and the artificial line and constituting the other two arms of the bridge circuit, a receiver connected across the bridge circuit between the junction of the transmission line and the artificial line and a point intermediate between the ends of said coil, a winding connected in parallel with said coil, a sender coupled to the winding, and means, including a circuit coupled with said coil for neutralizing in the sender current transmitted thereto by the winding due to unbalance in said bridge circuit arising from inequality of impedance of the transmission line and the artificial line. 30
4. In a balancing circuit arrangement for telephonic transmission, a bridge circuit comprising a transmission line constituting one of the arms of the bridge circuit, an artificial line constituting a second arm of the bridge circuit, and a coil having an iron core and constituting the two other arms of the bridge circuit, a receiver connected across the bridge circuit between the junction of the transmission line and the artificial line and a point intermediate between the ends of said coil, a winding connected in parallel with said coil, a sender coupled to the winding, and means for neutralizing in the sender current transmitted to the sender by the winding due to unbalance in the bridge circuit caused by inequality of impedance of transmission line and artificial line. 40
5. In a balancing circuit arrangement for telephonic transmission, a bridge circuit comprising a transmission line constituting one of the arms of the bridge circuit, an artificial line constituting a second arm of the bridge circuit, and a coil constituting the two other arms of the bridge circuit, a receiver connected across the bridge circuit between the junction of the transmission line and the artificial line and a point intermediate between the ends of said coil, a winding connected in parallel with said coil, a sender coupled to the winding, and means for neutralizing in the sender current transmitted to the sender by the winding due to inequality of impedance of transmission line and artificial line. 50
6. In a balancing circuit arrangement for telephonic transmission, a bridge circuit comprising a transmission line constituting one of the arms of the bridge circuit, an artificial line constituting a second arm of the bridge circuit, and a coil constituting the two other arms of the bridge circuit, a receiver connected across the bridge circuit between the junction of the transmission line and the artificial line and a point intermediate between the ends of said coil, a winding connected in parallel with said coil, a sender coupled to the winding, and means for neutralizing in the sender current transmitted to the sender by the winding due to unbalance in the bridge circuit caused by inequality of impedance of transmission line and artificial line, said means comprising a three-electrode vacuum tube having its grid circuit coupled with said coil and its plate circuit coupled with the sender, and said vacuum tube being arranged to act with respect to the currents received from the receiver due to unbalance of the bridge circuit as an amplifier and thus to produce a current of the strength required for neutralization in the sender of the current transmitted to the sender from the receiver by said winding, and also being arranged to act with respect to the currents received from the transmission line as a limiting tube so that the currents from the transmission line are not neutralized. 60
7. In a balancing circuit arrangement for telephonic transmission, a bridge circuit comprising a transmission line constituting one of the arms of the circuit, and artificial 125

- line constituting a second arm of the bridge circuit, and a coil constituting the two other arms of the bridge circuit, a receiver connected across the bridge circuit between the 5 junction of the transmission line and the artificial line and a point intermediate between the ends of said coil, a sender coupled to said coil, and means for neutralizing in the sender current transmitted to the sender 10 by the bridge circuit due to unequal impedance of transmission line and artificial line, said means comprising a thermionic vacuum tube coupled with the bridge circuit and with the sender.
- 15 8. In a balancing circuit arrangement for telephonic transmission, a bridge circuit comprising a transmission line constituting one of the arms of the bridge circuit, an artificial line constituting a second arm of 20 the bridge circuit, and a coil constituting the two other arms on the bridge circuit, a receiver connected across the bridge circuit between the junction of the transmission line and the artificial line and a point intermediate 25 between the ends of said coil, a winding connected with said coil, a sender coupled to said winding, and means for neu-

tralizing in the sender current transmitted to the sender by said winding due to unbalance of the bridge circuit caused by unequal 30 impedance of transmission line and artificial line, said means comprising a three-electrode vacuum tube having its grid circuit coupled with the bridge circuit and its plate circuit coupled with the sender, and said vacuum tube being arranged to act with respect to the currents received from the receiver due to unbalance of the bridge circuit as an amplifier and thus to produce a current of the strength required for neutralization in the 35 sender of the current transmitted to the sender from the receiver by said winding, and also being arranged to act with respect to the currents received from the transmission line as a limiting tube, so that the currents from the transmission line are not neutralized. 40

In witness whereof I hereunto set my hand in the presence of two witnesses.

Dr. ALEXANDER MEISSNER.
